CAP FOR A COSMETIC CONTAINER OR SIMILAR ARTICLE

Victor Silson, New York, N. Y., assignor to Helena Rubinstein, Inc., New York, N. Y., a corporation of New York

Application January 20, 1955, Serial No. 34,105

Term of patent 7 years

(Cl. D86—10)

Fig. 1

Fig. 2

Fig. 3

Fig. 4

Fig. 1 is a perspective view of a cap for a cosmetic container or similar article showing my new design;

Fig. 2 is a top plan elevational view of the same;

Fig. 3 is a side elevational view; and

Fig. 4 is a front elevational view.

I claim:

The ornamental design for a cap for a cosmetic container or similar article, substantially as shown.
